UNITED STATES PATENT OFFICE.

ALWIN SCHROEDER, OF BROOKLINE, MASSACHUSETTS.

INTERPRETATIVE MUSICAL NOTATION.

1,171,467.

Specification of Letters Patent. Patented Feb. 15, 1916.

Application filed July 16, 1915. Serial No. 40,198.

To all whom it may concern:

Be it known that I, ALWIN SCHROEDER, a citizen of the United States, residing at Brookline, in the county of Norfolk and State of Massachusetts, have invented certain new and useful Improvements in Interpretative Musical Notation, of which the following is a specification.

My invention relates to a system or manner of musical notation intended to indicate to the performer nuances of musical tempi; and is particularly intended for use in musical compositions written for instruments, such as piano, violin, cello, etc.

In modern musical notation, the basis of time value is the whole note or semi-breve; the time values of various shorter notes being aliquot parts of this whole note, such as $\frac{1}{2}$, $\frac{1}{3}$, $\frac{1}{4}$, $\frac{1}{8}$, $\frac{1}{16}$, $\frac{1}{32}$, etc. These rigid divisions of the time-value are often insufficient to indicate that duration of the notes or tones, which should be given to produce the proper musical interpretation of the written music. The same group of notes played with mathematical accuracy according to the written score, will when played with the proper variations in time, produce quite a different effect. In the one case the effect is colorless, while in the other there is a shading or coloring, which produces a far livelier impression.

In the accompanying drawing,—Figures 1, 2 and 3 are separate lines of music, indicating the manner in which my interpretative notation is carried out.

In Fig. 1 each group of notes has four sixteenth notes, but in group 1, the first three notes are more widely spaced, indicating that, while the whole group is to occupy substantially the time of a quarter note, the first three, instead of each being in duration a strict sixteenth note, are each a little longer than a sixteenth note, the fourth note being somewhat less. It will be noted also that the first and third, and fifth and seventh groups of sixteenth notes are identical; but, according to my notation, the first three notes of the first and fifth groups would be given a time duration differing from that given to the same notes occurring in the third and seventh groups, this difference being indicated by the spacing. The remaining groups would be played as sixteenth notes having all the same value.

In Fig. 2, the first note of the first group is spaced more widely from the second note,

the second, third, and fourth notes being separated by equal distances, thus indicating that this first note is to be given a greater duration than one-sixteenth, while the other notes are of equal but correspondingly shorter duration. Similarly, the first notes of the third and fifth groups of this figure, are indicated as having a longer duration than the other notes of their respective groups. The remaining groups would be played according to the indicated value, viz., as sixteenth notes.

In Fig. 3, I have shown an additional use of spacing between the notes to indicate, particularly in the music of songs, the "luftpause" or point at which breath is to be taken. This space is left, as indicated at the end of the first bar on Fig. 3, between the last note of one phrase or figure and the beginning of the next, and may occur either at the end of a bar or measure or at some intermediate point within the measure.

By my invention these interpretative indications are placed directly within the area at which the eye of the performer must look in order to read the music; and he is not required to focus his eyes on time marks or indications above or under the notes but is enabled to observe these indications when looking at the notes themselves.

I am aware that in modern musical notation there are various ways of giving to a note having a certain indicated time value, a longer or shorter duration, such as the dotted note, grace note, etc., but these are not sufficient to indicate coloring or shading which can be shown by my interpretative printing.

I am not aware that it has before been suggested to afford to the performer a simple indication such as that above described, whereby he may be guided in the slight variations in time, which though small in themselves, produce a wide difference in musical effect.

It will be noted that my system does not involve any change in the ordinary methods of printing music except such lateral spacing of the notes as may be required to indicate the proper interpretation or performance of some particular passage; and that my system permits the use of all the usual indications of time, emphasis, etc., but adds a new feature which assists in the more artistic rendition of written music, by which is provided a means by which the performer

is enabled to give to the music a reading in accordance with that interpretation which is given by a master in the art.

I claim:—

5. 1. A system of interpretative musical notation in which spaces wider than those required in the ordinary printing are provided between notes or groups of notes to assist the performer in the rendition of the 10 music, substantially as and for the purpose described.

15. 2. A system of interpretative musical notation in which the several notes of a group of notes, all of which have the same indicated time-value, are separated by spaces, not all of which are equal, the spacing corresponding to the duration to be given to the notes in performance of the 20 music, whereby nuances of tempi are indicated, substantially as and for the purpose described.

25. 3. A system of interpretative musical notation in which the several notes of a group of notes are separated by spaces, not

all of which are equal, the spacing corresponding to the duration to be given to the notes in performance of the music, whereby nuances of tempi are indicated, substantially as and for the purpose described. 25

30. 4. A system of interpretative musical notation in which spaces wider than those required in the ordinary printing are provided between the end of one phrase or figure and the beginning of the next, substantially for the purpose described. 35

35. 5. A system of interpretative musical notation in which the several notes of a group of notes are separated by spaces, not all of which are equal, the spacing corresponding to the duration to be given to the 40 notes in performance of the music, and wider spaces provided wherever desirable between the ending of one phrase and the beginning of the next, substantially as and for the purposes described. 45

In testimony whereof I affix my signature.

ALWIN SCHROEDER.
